EGG POACHER

Thomas V. Denning, Anaheim, and Peter M. Herrema,
Los Angeles, Calif.

Application September 28, 1959, Serial No. 57,708

Term of patent 14 years

(Cl. D44—1)

Fig. 1 is a perspective view of an egg poacher showing our new design;

Fig. 2 is a side elevational view;

Fig. 3 is a top plan view in enlarged scale.

Fig. 4 is a bottom plan view in enlarged scale; and

Fig. 5 is a front elevational view in enlarged scale.

Essential features of the design are shown in full lines.

We claim:

The ornamental design for an egg poacher, substantially as shown and described.
